MULTIPLE COUNTER CALCULATING AND
REGISTERING MACHINEJohn Emil William Greve, Chemnitz, Germany,
assignor to the firm Astrawerke Aktiengesell-
schaft, Chemnitz, GermanyApplication July 22, 1932, Serial No. 624,129
In Germany July 25, 1931

4 Claims. (Cl. 235—60)

This invention relates to a multiple counter calculating and registering machine, wherein the counting mechanisms are brought into operative position relatively to their driving means 5 by a movable frame in which they are provided. It is known in connection with machines of this type to move the counting mechanism frames, which are designed as carriages or rotatable drums, by a special source of power but these machines have the drawback that the setting of the counting mechanisms, that is to say the movement of the counting mechanism frames, is dependent on the extent of the movement of their controlling member, for instance, 10 the paper carriage. It is therefore not possible in connection with these machines to bring into operative position any desired counting mechanism with the slightest movement of the paper carriage or even by a key depression.

20 The present invention obviates these drawbacks.

A constructional form of the invention is shown by way of example in the accompanying drawings, wherein the counting mechanisms are 25 provided in a drum.

Figure 1 is a longitudinal section through the machine.

Figure 2 is the arrangement of the drum as viewed from above.

30 Figure 3 is a view of the locked setting keys. Figure 4 represents the adjustment by studs as viewed from above.

Figure 5 is a diagrammatic view thereof as viewed in front.

35 Figure 6 is an end view of some keys.

Fig. 7 is a fragmentary horizontal sectional view taken through the lower parts of the keys and showing the arrangement of the bell crank levers connected therewith;

40 Fig. 8 is a transverse sectional view through the toothed bar showing one of the guide bails therefor.

The counting mechanism drum is mounted 45 below the bed plate 1 on a shaft 2 which is secured by bearings 3 and 4. The said drum comprises a hub 5 and side walls 6 and 7 which bear the axes 8 of sixteen counting mechanisms 9. These counting mechanisms are driven by rack bars 10 which are connected to the type carriers 11 of the machine. The counting mechanisms are brought into operative position relatively to the said driving means by rotating the drum. In the construction shown by way 50 of example the control for the drum is arranged in such a manner that it can be effected automatically by the movement of the paper carriage of the machine as well as independently thereof by depressing keys. For this purpose there are provided in the front left part of the machine two rows of keys with 55 eight keys in each row so that a key is provided for each counting mechanism in the drum. The keys 12 are each formed of two parts, an upper part and a lower part; the upper part is provided with a button and is moved in slots of the guides 13, 14 carried by side walls 15, 16 and abuts with its longitudinally movable neck against the lower part 19. The lower key parts 19 are moved in slots 60 between two further guides 17, 18 which are 65 also secured to the side walls 15, 16. They are each provided with a pin 20 at their lower end. There is provided on the guide 18 a locking bar 22 which is subjected to the action of a spring 21. The locking bar 22 is provided 70 with slots through which the key parts 19 extend. If one of the keys 12 is depressed, the locking bar will be forced apart by the projection 23 of the key part against the tension of the spring 21 and the bar 22 will jump 75 over the projection 23 as soon as the part 19 is pressed low enough as is shown in Figure 1 in connection with the depressed key. If another key is depressed, its projection 23 will again open the locking bar 22 so that the previously depressed key will return to its normal position in consequence of the tension of a spring 39 the arrangement and operation of which will be hereinafter described. The locking bar 22 is provided with two rows of slots 80 so that it acts on both rows of keys. Bell crank levers 24 are rotatably mounted at the side frames 15, 16 on stop screws 25 and their bifurcated arm engages with the pin 20 of the lower key part 19. The bell crank lever 24 is 85 connected to a link 26 the other end of which is connected to a lever arm 27. The lever arm 27 is secured on a shaft 28 which is mounted between two side plates 29, 30. The extended shaft 2 of the counting mechanism drum extends through a third bearing 31 below the bed plate 1 and the hub of this bearing is turned in such a manner that the bushing 32 which is riveted in the plate 30 fits over the same. The plate 30 is prevented by a screw 33 from being 90 twisted and from sliding off the turned end of the hub. The plate 29 is secured to the plate 30 by means of bolts 34, 35, 36 and nuts so that the two plates constitute a double-sided bearing 95 for the shaft 28. There is secured between the 100

55 110

two plates on the shaft 28 a stop or abutment 37 which cooperates with a lever arm 38 which is rigidly secured to the shaft 2 and is also located between the two plates 29 and 30. There 5 is connected to the lever arm 27 a spring 39 which always tends to draw the stop 37 out of the path of the arm 38 into the position indicated in Figure 1 by dotted lines. By means of the link 26 and bell crank lever 24, the 10 depressed key 12 and the lower key end 19 are again returned to the normal position when another key is depressed.

Since in the present case the counting mechanism drum has sixteen counting mechanisms, 15 sixteen stops 37 are also provided between the two walls 29 and 30 and the lever arms 27 are connected by links 26 to the corresponding keys 12 or to their bell crank levers 24.

In order that the setting or adjusting arm 20 38 of the counting mechanism drum may move from its position of rest to the new stop 37 when depressing one of the keys 12, a special source of power is provided whereby the counting mechanism drum or its setting arm 38 is 25 always rotated in the direction of the arrow. In connection with the calculating machines with manual drive a spring motor is preferably employed for the said purpose; during each operation of the machine the spring of the 30 said motor is tensioned and the motor therefore always maintains its full power. In the present case it is a question of a machine with electric drive; consequently the rotary movement for the drum is preferably driven directly therefrom. An intermediate shaft 40 which is adapted 35 to automatically return the paper carriage to its end position is constantly rotated by the motor of the calculating machine in the direction of the arrow. The said shaft has a sprocket wheel 41 by which a wheel 42 is driven through the medium of a chain the said wheel 42 being loosely mounted on the drum shaft 2. A friction clutch 43 is provided between the sprocket wheel 42 and the shaft 2 so that the counting 40 mechanism drum would always rotate in the direction of the arrow if its setting arm 38 would not prevent it from doing so by one of the stops 37. By depressing a further key 12, the previously operated key will be released again, as 45 already described, and will be jerked upwards by the tension of the spring 39 whereupon its stop 37 will move out of the path of the setting arm 38 so that the latter may now freely rotate until it abuts against the new stop 37.

50 Means are provided in the present machine whereby the counting mechanisms of the drum may be brought into operative position relative to their driving means 10 not only by the keys 12 but also automatically through the medium of studs 72 which are previously adjusted on the paper carriage or on another movable part of the machine. For this reason, the keys 12, 19 are made of two parts and the upper key part has a slot 44 Figure 6 through which 55 a bar 45 provided with rising surfaces extends. Consequently there is located in each row of keys a bar 45 one end of which has a hole 46 wherein a pin 47 of a hand lever 48 extends. The lever 48 is rotatably mounted on a stationary pin 49 in the side frame of the machine and 60 its lower arm is designed as a segment 50 engaging with a toothed wheel 51 which is keyed on a shaft 52 mounted below the bed plate of the machine in the brackets 53, 54. A second 65 wheel 55 which is rigidly secured to the other

end of the shaft 52, drives a toothed bar 56 which engages with its other end with another toothed wheel 57 which is rigidly secured to the lower end of an eccentric shaft 58. The bar 56 is maintained in engagement with the 80 toothed wheels by bails 59, 60 which are secured to the bed plate of the machine. The eccentric shaft 58 is provided with its turned ends 61, 62 in bearing brackets 63, 64 which are secured by screws 65, 66 to the side frame of the 85 machine.

Sixteen levers 67, 68 engage with their eyes over the eccentric 58 the said levers being superposed and spaced apart by guiding fingers 69, 70. The said guiding fingers are secured to the 90 frame walls of the machine. The levers 67, 68 are provided approximately in their center with projections 71, 71' cooperating with one of the studs 72. The tapered end of the lever arms is provided with links 73 the other end of which is connected to the bell crank levers 24. In the position shown in Figure 4, a stud 72 presses against the projection 71' of its corresponding levers 67, 68 whereby the latter is swung into the 95 position as indicated. Its link 73 thereby swings the corresponding bell crank lever 24 and through the medium of its link 26, the corresponding arm 27 is swung against the tension of its spring 39 and the setting member 37 connected to the said lever arm is moved into the 100 path of the setting arm 38 of the drum.

Owing to the handle 48 being shifted out of the position 48' into the position shown in Figure 3, the two bars 45 have locked all the keys by their inclined teeth 45' which extend through 110 the slots of the keys after they have also raised the upper part of the last depressed key the lower part 19 of which is however left in the depressed position and is only freed from this position by the adjustment of a new stop 37 by studs 72 or levers 67, 68. The lower key part 19 belonging to the newly adjusted stop 27 is then arrested by the locking bar 22 in the same manner as previously described.

In order that the hand lever 48 may be 120 brought out of its position 48' into the position shown in Figure 3, its toothed end 50 through the medium of the toothed wheel 51 causes the shaft 52 to be rotated through an angle of about 180°. By means of the toothed bar 56 engaging 125 with the toothed wheel 55 and through the medium of the toothed wheel 57, the eccentric shaft 58 is also rotated through an angle of about 180° whereby the ends of the setting lever 67 are swung in such a manner that the projections 71 of the levers come within the range 130 of the studs. By shifting the hand lever 48 not only the keys 12 are prevented from operating but also the levers 67, 68 are brought into operative position by the rotation of the eccentric shaft 58. The hand lever 48 is secured in its end positions by a spring actuated check lever 74 which cooperates with a pin 75 of the lever.

A cage is secured between the side walls 76, 77 140 of the paper carriage for receiving the adjustable studs 72 the said cage comprising two slotted plates 78, 79 and a hinged cover 80. The cover is hinged at 81 and is arrested in a closed position by a pawl 82. There are provided in the plates 78, 79 sixteen rows of slots wherein studs 72 may be inserted. The vertical spacing of these slots is the same as the vertical spacing of the setting levers 67, 68 so that the studs 72 correspond in their elevated position with 145 150

the projections 71. The operation of these parts is as follows:

In order to work in vertical columns on a sheet, the sheet is placed around the writing roller 83 in the paper carriage 76 the tabulating device of which is adjusted by studs 84 in the known manner so that when operating the machine the paper carriage moves from one stud 84 to the next one. The relative spaces of the 10 studs 84 represent the width of the columns of the sheet. When the columns are divided by inserting the studs 84 the cover 80 will be opened and a stud 72 inserted in the slots of the plates 78, 79. It is readily obvious that the selection 15 of the counting mechanism which is to work in the respective column is only dependent on the height of the row of slots wherein the respective stud 72 is inserted. When the stud 72 is co- 20 ordinated in accordance with the intended work to the tabulating studs 84 the cover 80 will again be closed whereby the stud 72 will be prevented from falling out.

If the adjustment or setting of the counting mechanisms is now automatically effected by the 25 carriage movement through the medium of studs 72, it is nevertheless still possible notwithstanding the adjusted studs 72 to also work in each column with any of the counting mechanism than that which is coordinated to the stud if 30 this should be necessary for some reason or other. For this purpose merely the handle 48 is again brought into the position 48' whereby the 35 keys 12 are again freely depressible. At the same time the shaft 51 and the transmission rod 56 of the eccentric 58 are moved through the medium of the segment 50 in such a manner that the projections 71 of the setting arms 67, 68 move out of the range or path of the studs 72. The counting mechanism operated by the 40 studs 72 of the respective column remains in operative position and its stop 37 remains in the path of the setting arm 38 of the drum because the corresponding lower key part 19 is arrested by the locking bar 22. When another counting 45

mechanism is operated by the depression of keys a new stop 37 is inserted and the lower key part 19 previously arrested in the operated position thereby returns to the normal position in the above described manner. It is thus possible to work in each column of the sheet with any desired counting mechanism notwithstanding the adjustment of the studs 72.

The herein described counting mechanism control is so arranged that machines may be supplied wherein the control is effected automatically by studs previously adjusted on the paper carriage or also machines without paper carriage wherein the counting mechanisms are operated by keys. Moreover machines may be supplied wherein both setting systems are provided as shown in the drawings.

What I claim is:

1. A multiple counter calculating and registering machine including a drum, counting mechanisms in said drum, a special source of power for driving said drum, driving means associated with the counting mechanisms, said drum being adjustable to various positions to selectively bring the counting mechanisms into 100 operative relation to the driving means, and selectively operable stops coating with said drum, said drum being adapted to be adjusted by said source of power from any position directly to the selected stop. 105

2. A machine as claimed in claim 1 characterized in that the several stops are arranged concentrically about the axis of said drum and cooperate with an arm carried by said drum.

3. A machine as claimed in claim 1 characterized by the provision of keys associated with said stops, studs adapted to automatically adjust said stops, and means for locking said keys when the studs are conditioned to control totalizer selection. 110

4. A machine as claimed in claim 1 characterized in that said special source of power is operated continuously.
